UNITED STATES PATENT OFFICE.

ELLIS W. TEST, OF MICHIGAN CITY, INDIANA.

SHEET-METAL CAR END.

1,408,657.

Specification of Letters Patent. Patented Mar. 7, 1922.

Application filed August 8, 1921. Serial No. 490,575.

To all whom it may concern:

Be it known that I, ELLIS W. TEST, a citizen of the United States, and resident of Michigan City, county of Laporte, and State 5 of Indiana, have invented certain new and useful Improvements in Sheet-Metal Car Ends, of which the following is a specification and which are illustrated in the accompanying drawings, forming a part thereof.

10 The invention relates to car ends formed of sheet metal plates or a single plate for cars of the gondola type, the plate being pressed to form corrugations. The improvement appertains to the arrangement or 15 configuration of the corrugations and the invention consists of a structure such as is hereinafter described and as illustrated in the accompanying drawings in which—

Fig. 1 is a detail side elevation of the body 20 of a box car;
Fig. 2 is an end elevation thereof;
Fig. 3 is a detail section on the line 3—3 of Fig. 2, and
Fig. 4 is a detail section on the line 4—4 25 of Fig. 2.

In the drawings there is shown the body 10 of a box car and because of the height of the car the end is formed of two plates 11, 12, which are of substantially the same form 30 and hence, as to the main features but one need be described. Each of these plates is provided with side marginal flanges 13, 14, overlapping the corner posts of the car and to which they may be suitably secured.

35 The central portion of the plate, as 12, is bulged outwardly, as shown at 15, and this distortion of the plate preferably takes an oval form, the longer axis of the oval being horizontal.

40 Intermediate of the ends of the portion 15 and the side margins of the plate the latter is distorted by a depression inward, as shown at 16, this depression extending along the upper and lower margins of the oval for 45 a considerable distance and hence taking substantially a U shape. Between the depressions 16 and the margins of the plate the latter remains in its original plane.

The lower margin of the upper plate over- 50 laps the upper margin of the lower plate and the two plates are secured together by a series of rivets 17. The upper margin of the

lower plate may be bent or flanged inwardly, as shown at 18, this flange not only stiffening the end of the car but affording means 55 for attaching to the end a nailing stringer 19 to which a lining 20 for the car end may be secured, thereby avoiding the necessity for perforating the sheet metal plates for the accommodation of attaching bolts and 60 obviating the danger of leaky bolt holes.

The described arrangement of the corrugations secures great strength to resist the pressure of shifting lading without materially increasing the length of the car. The 65 central portion of the plate being bulged outwardly, the deflection from the plane of the plate being in all directions, an arch is formed and outward pressure is resisted largely by the tensile strength of the metal, 70 the lines of resistance being distributed throughout the entire area of the bulge. The inward depressions around the ends of the oval bulge shorten the arch and increase 75 its strength. They also add to the strength of the plate in that they constitute vertical corrugations.

The particular configuration of the distortions of the central portion of the plate may be varied without departing from the scope 80 of the invention, which will include any form in which the plate has a central bulge, surrounded at least in part by depressions secured by pressing the plate in the opposite direction from its original plane. 85

I claim as my invention:

1. A car end comprising a sheet metal plate having flat marginal portions, a central outward bulge, and end depressions bordering the bulge and merging into the central outward bulge and the flat marginal portions. 90

2. A car end comprising a sheet metal plate having flat marginal portions, inward depressions across the plate adjacent the marginal portions and a central outward bulge merging into the depressions. 95

3. A car end comprising a sheet metal plate having flat marginal portions, a central outward bulge oval in form, and inward 100 depressions bordering and merging into the ends and portions of the sides of the oval.

4. A car end comprising a sheet metal plate having flat marginal portions, a cen-

tral outward bulge, and inward depressions of substantially U-shape bordering and merging into the ends and portions of the sides of the central bulge.

5. A car end comprising a sheet metal plate having flat marginal portions, a central outward bulge, and inward depressions

bordering and merging into the ends and portions of the sides of the central bulge.

6. A car end comprising a sheet metal 10 plate having flat marginal portions, a central outward bulge, and inward depressions in said flat marginal portions.

ELLIS W. TEST.
